FUEL ADMISSION DEVICE FOR INTERNAL-
COMBUSTION ENGINES

Arthur Sandhofer, Cisco, Tex., assignor to Phillips Petroleum Company, a corporation of Delaware

Application August 23, 1940, Serial No. 353,941

10 Claims. (Cl. 123—92)

This invention relates to internal combustion engines and in its more specific aspects to improvements in fluid fuel admission means for internal combustion engines.

Heretofore, it has generally been the practice in the operation of two cycle engines to introduce the fluid fuel under pressure to the head end of the cylinder during the compression stroke of the piston by means of a fuel injector which includes a valve, a valve stem and a spring. The valve is opened through its cooperation with a rocker arm and a push rod or valve shaft, the latter being actuated by a geared connection to the crank end of the engine. After the fuel has been introduced into the cylinder, the above mentioned spring tends to close the valve. The "timing" (opening and closing) of the valve is controlled by a cam which operates one end of the rocker arm at predetermined intervals to open and close the valve.

The present invention is an improvement over the invention disclosed in the copending patent application of Jim Barton, inventor, Serial No. 269,777; and contemplates the admission of fuel into the head end of an internal combustion engine cylinder by means of a device which comprises a gas valve, a valve stem, a spring, and a diaphragm or other form of movable partition, cooperatively arranged with respect to a plurality of control valves so that the gas valve is operated by the alternate pressure and vacuum created behind the piston during the expansion and compression strokes of the piston. A small bore conduit places my device in communication with the back end of the engine cylinder; and, as the piston moves forward in each compression stroke, a partial vacuum is created behind the piston and also in my device. When the piston moves toward the back end of the cylinder on each expansion stroke, a pressure is produced in the conduit, which pressure is utilized to actuate the diaphragm to open the gas valve and admit fuel into the cylinder. I am able to accurately control the point in the engine cycle at which the fuel admission valve is alternately opened and closed in order to obtain optimum fuel economy and operating results by employing a simple, dependable and trouble-free device instead of by means of the complicated troublesome mechanism that was used in the past. The practice of my invention eliminates the conventional rocker arm, push rod, cam and gear arrangement, and effects a number of advantages which will be readily understood by those skilled in the art on a perusal of the accompanying drawings.

in conjunction with the detailed description hereinafter presented.

It is the primary object of this invention to provide a fuel admission device which is adapted to increase the power delivered by internal combustion engines.

Another object of this invention is to provide a device of the character indicated which will effectively and efficiently control the admission of fuel into an internal combustion engine so that the engine may be operated under various load conditions at economical fuel consumption.

A third object of my invention is to provide a fuel admission device which is operable in a positive and dependable manner by alternate pressures and vacua created behind the piston of an internal combustion engine during the expansion and compression strokes of the piston.

This invention has for a further object the provision of an internal combustion engine fuel admission device which is simple in design, rugged in construction and relatively inexpensive to manufacture. By virtue of the simplicity of my design and the few moving parts that are subject to wear, the maintenance and replacement costs are reduced to a minimum.

A still further object of this invention is to provide a fuel admission device which is adapted to be readily substituted for other devices that are employed for the same purpose. This conversion may be quickly and inexpensively accomplished at the place of use, thereby avoiding costly delays which would result if the entire engine had to be returned to the factory or transported to a workshop which is especially equipped to make the conversion.

These as well as additional objects and advantages will be apparent by reference to the following specification and annexed drawings which respectively describe and illustrate a preferred embodiment of my invention, and wherein

Figure 1 is a longitudinal cross section view through the center of an internal combustion engine cylinder having my invention operatively connected thereto;

Figure 2 is an enlarged elevation view of my device in quarter section;

Figure 3 is a top plan view of the device illustrated in Figure 2, partly in cross section; and

Figure 4 is a vertical cross section view of the fluid chamber with the cover plate omitted taken along line 4—4 of Figure 3.

Referring to the drawings and more particularly to Figure 1, I have denoted therein an internal combustion engine cylinder 10, which is

provided with the usual water-jacket 11 and is rigidly supported on an engine frame 12 by means of bolts 13. A piston 14 reciprocates within the cylinder and is connected to a piston rod 15 which passes through a packing gland 16 in the back end of the cylinder. A conventional spark plug 17 and air starting valve 18 are indicated at the head end of the cylinder. Air for normally operating the engine is introduced from the outside into an air inlet passageway 19, passes through air inlet valves 20 and chamber 21, and thence is admitted into the cylinder by way of inlet ports 22 and 23. The products of combustion are emitted from the cylinder by way of exhaust ports 24 and an exhaust outlet 25 communicating therewith.

A body member, generally indicated by reference numeral 26, includes a base member 21, a pair of supports 28, a valve actuating chamber 29 and a fluid chamber 30 having a cover plate 31, all assembled into a unitary structure by any suitable means known in the art. Base member 27 embraces a fuel chamber 32 that is provided with a tapped fuel inlet opening 33 for connection to a source of fuel supply (not shown), and is securely mounted to the head end of the cylinder so that a seat 34 for a fuel valve 35 is substantially flush with the inner surface of the cylinder head, as shown in Figure 1. Valve 35 has a stem 36 slidable in a guide 37 in fuel compartment 32 and extends through a conventional type of packing unit 38 consisting of a packing nut 39, a follower ring 40 and packing material 41. The upper extremity of valve stem 36 is threaded to engage with corresponding internal threads in a diaphragm plate 42. A spider 43 supports a compression spring 44 that is concentrically disposed with respect to the valve stem for urging diaphragm plate 42 and valve stem 36 in an upward direction to normally maintain fuel valve 35 in closed position. As will be apparent from an inspection of Figure 2, compression spring 44 is also adapted to urge a diaphragm 45, which constitutes the lower wall of actuating chamber 29, in an upward direction to thereby seat the diaphragm against the lower end of a diaphragm seating orifice or conduit 46 which establishes communication between valve actuating chamber 29 and fluid chamber 30.

Referring next to fluid chamber 30, it will be observed that a casting 47 forming the main part of this chamber has a bottom portion 48 that also serves as the top wall for valve actuating chamber 29. Integral with casting 47 is a manifold 49, illustrated in detail in Figure 3, which has a fluid passage 50 that is tapped at 51 for connection to a relatively small bore conduit 52 which communicates with the back end of the cylinder through chamber 21 and ports 22 and 23 in the order set forth. Passage 50 communicates with the interior of chamber 30 through a threaded fitting 53 that is provided with a plurality of lateral ports 54, a central passage 55 and a second set of lateral ports 56. The flow of fluid from passage 50 into chamber 30 is controlled by an adjustable needle valve 57 which is in threaded engagement with fitting 53. This needle valve is effectively sealed against leakage by means of a threaded packing ring 58 which compresses a packing material 73 around the needle valve stem. Another valve in fitting 53, including a ball check 59 and a compression spring 60 which is disposed between the ball check and a retaining disc 61, permits fluid to flow from passage 50 into chamber 30, but pre-

vents fluid flow in the opposite direction. While this check valve arrangement is recommended for use with my invention, it is to be understood that it is not essential to successful operation in practice.

Passage 50 also communicates with the interior of chamber 29 through a pair of passages 62 and 63 which interconnect with cross passages 64 and 65, respectively. A needle valve 66 which is 10 threadedly contained in manifold 49 is positioned to control the admission of fluid into passage 62 and is provided with sealing means consisting of a threaded plug 67 and packing material 68. An adjusting screw 69 is packed off with respect to manifold 49 through the cooperation of a threaded plug 70 and packing material 71. Adjusting screw 69 controls the movement of a ball check valve 72 which is utilized to prevent fluid in passage 50 from entering passage 63, but allows 20 fluid in chamber 29 to flow through passages 65 and 63, and thence into passage 50.

For the purpose of outlining the mode of operation of the present invention, it is first assumed that piston 14 is moving in the direction indicated 25 by the arrow on piston rod 15, that is, to the left or toward the head end of the cylinder. It will be noted that air ports 23 and exhaust ports 24 are all covered by the piston during this, the compression stroke of the piston. Starting valve 30 18 and fuel valve 35 are both closed, as indicated in the drawings; and the fuel and air mixture previously admitted to the cylinder is compressed preparatory to firing. During this step in the 35 operation, a partial vacuum is created in back 35 of the piston, extending from the back end of the cylinder through air port 22, air chamber 21, conduit 52 and lastly to passage 50 in manifold 49. This permits the withdrawal of fluid from chamber 29 through passages 65 and 63 and passages 40 64 and 62. The effect of this partial vacuum is to permit compression spring 44 to urge fuel valve 35 into completely closed position and move diaphragm 45 upwardly, bringing it against the lower end of conduit 46, as illustrated in Figure 2. 45 As the piston moves in the opposite direction during its expansion stroke, it will uncover exhaust ports 24 before air ports 23, allowing the products of combustion to exhaust by way of outlet 25. Air admitted by inlet 19 and valves 20 into chamber 21 is introduced to the head and back ends of the cylinder by ports 23 and 22, respectively. Continued travel of the piston in its expansion stroke compresses the air admitted into the back end of the cylinder and transmits 50 this air under pressure through port 22, chamber 21, conduit 52 and thence into passage 50. A portion of this air is bled by needle valve 66 through connecting passages 62 and 64 into actuating chamber 29. Another portion of this air 55 under pressure is admitted through the various passages in fitting 53 into fluid chamber 30. As soon as a sufficient amount of air under pressure is introduced into chamber 29, it will move the diaphragm downwardly a very small distance, for example, a few thousandths of an inch. This will unseat the diaphragm from conduit 46, permitting fluid in chamber 30 to rush into chamber 29, thereby snapping valve 35 into open position against the action of compression spring 44. It 60 will be apparent that the effect of the fluid admitted into chamber 29, while the diaphragm is against conduit 46, is to serve as a "trigger" and release the air in chamber 30 at predetermined times during the engine cycle to urge fuel valve 65 35 into open position at the desired instant. By 70

properly adjusting needle valves 66 and 57, the fuel valve may be opened to admit fuel to the cylinder just as the piston starts to move in its compression stroke. When an engine cylinder and piston arrangement of the character illustrated in Figure 1 is employed, it is of course desirable that the various control valves be adjusted to delay the admission of fuel into the cylinder until after the exhaust ports are closed during the compression stroke of the piston, thereby eliminating fuel waste which would otherwise occur. It is therefore obvious that the fuel valve may be opened at any predetermined instant during the engine cycle and thus introduce fuel into the cylinder at the most opportune time to obtain maximum benefits and economical operation.

From the foregoing it is believed that the construction, operation and advantages of my instant invention will be readily comprehended by persons skilled in the art. It is to be clearly understood, however, that the form of my invention herewith shown and described is to be taken as a preferred example of the same and that various changes in the shape, size and arrangement of parts may be resorted to without departing from the spirit of the invention as defined by the appended claims.

I claim:

1. A mechanical assemblage comprising an engine having a fuel injector valve, a working cylinder having a fluid conduit extended off therefrom, a piston reciprocable in the cylinder and periodically causing fluid compression and suction impulses in said conduit, and means coupled to the conduit responding automatically to said periodic impulses of both kinds to store compressed fluid with which to impress force upon the valve for its periodic opening.

2. A mechanical assemblage comprising an engine having a fuel injector valve, a working cylinder having a fluid conduit extended off therefrom, a piston reciprocable in the cylinder and periodically causing fluid compression and suction impulses in said conduit, and means coupled to the conduit responding automatically to said periodic impulses of both kinds to store compressed fluid with which to impress force upon the valve for its periodic opening, said means including a housing, a fixed partition dividing the interior of the housing into a fluid chamber and a valve actuating chamber, a movable partition forming a wall of the actuating chamber and coacting with the valve to operate the same, and means including a plurality of passages communicating with the conduit and the chambers.

3. A mechanical assemblage comprising an engine having a fuel injector valve, a working cylinder having a fluid conduit extended off therefrom, a piston reciprocable in the cylinder and periodically causing fluid compression and suction impulses in said conduit, and means coupled to the conduit responding automatically to said periodic impulses of both kinds to store compressed fluid with which to impress force upon the valve for its periodic opening, said means including a housing, a fixed partition dividing the interior of the housing into a fluid chamber and a valve actuating chamber, a movable partition forming a wall of the actuating chamber and coacting with the valve to operate the same, and means including a plurality of valve controlled passages communicating with the conduit and the chambers.

4. In a device for admitting fuel into an inter-

nal combustion engine having a working cylinder and a piston reciprocable therein, the improvement comprising a normally closed fuel valve adapted to control the admission of fuel into the cylinder, a fluid chamber, a valve actuating chamber including a movable partition for cooperating with the valve to open the same, a port for establishing communication between the fluid chamber and the valve actuating chamber, means for normally closing the port, said means responding to predetermined movement of the partition in one direction to open the port, and means including a plurality of passages adapted to communicate with the cylinder for introducing and withdrawing fluid under pressure into and from the chambers during each complete cycle of the engine.

5. In a device for admitting fuel into an internal combustion engine having a working cylinder and a piston reciprocable therein, the improvement comprising a normally closed fuel valve adapted to control the admission of fuel into the cylinder, a fluid chamber, a valve actuating chamber including a movable partition for cooperating with the valve to open the same, a port for establishing communication between the fluid chamber and the valve actuating chamber, means for normally closing the port, said means responding to predetermined movement of the partition in one direction to open the port, and means including a plurality of valve controlled passages adapted to communicate with the cylinder for introducing and withdrawing fluid under pressure into and from the chambers during each complete cycle of the engine.

6. In a device for admitting fuel into an internal combustion engine having a working cylinder and a piston reciprocable therein, the improvement comprising a fuel valve adapted to control the admission of fuel into the cylinder, means for normally maintaining the valve in closed position, a fluid chamber, a valve actuating chamber, a movable partition forming a wall of the actuating chamber, said partition responding to fluid pressure for operating the valve against the action of said means, a port for establishing communication between the fluid chamber and the valve actuating chamber, means for normally closing the port, said last mentioned means responding to predetermined movement of the partition in one direction to open the port, and means including a plurality of passages adapted to communicate with the cylinder for introducing and withdrawing fluid under pressure into and from the chambers during each complete cycle of the engine.

7. In a device for admitting fuel into an internal combustion engine having a working cylinder and a piston reciprocable therein, the improvement comprising a fuel valve adapted to control the admission of fuel into the cylinder, means for normally maintaining the valve in closed position, a housing associated with the valve, a fixed partition dividing the interior of the housing into a fluid compartment and a valve actuating compartment, a movable partition forming a wall of the actuating compartment and responding to fluid pressure for operating the valve against the action of said means, a port for establishing communication between the fluid compartment and the actuating compartment, means for normally closing the port, said last mentioned means responding to predetermined movement of the partition in one direction to open the port, and means in-

cluding a plurality of passages adapted to communicate with the cylinder for introducing and withdrawing fluid under pressure into and from the chambers during each complete cycle of the engine.

8. In a device for admitting fuel into an internal combustion engine having a working cylinder and a piston reciprocable therein, the improvement comprising a fuel valve adapted to control the admission of fuel into the cylinder, means for normally maintaining the valve in closed position, a housing associated with the valve, a fixed partition dividing the interior of the housing into a fluid compartment and a valve actuating compartment, a movable partition forming a wall of the actuating compartment and responding to fluid pressure for operating the valve against the action of said means, a port for establishing communication between the fluid compartment and the actuating compartment, means for normally closing the port, said last mentioned means responding to predetermined movement of the partition in one direction to open the port, and means including a plurality of valve controlled passages adapted to communicate with the cylinder for introducing and withdrawing fluid under pressure into and from the chambers during each complete cycle of the engine.

9. In a device for admitting fuel into an internal combustion engine having a cylinder, a conduit establishing communication between the interior and the exterior of the cylinder, and a piston reciprocable in the cylinder, the improvement comprising a fuel valve adapted to control

the admission of fuel into the cylinder, a fluid chamber, a valve actuating chamber including a movable partition for cooperating with the valve to actuate the same, means for placing the fluid chamber in communication with the actuating chamber, and separate means including a plurality of valved passages adapted to communicate with the conduit for supplying and subsequently withdrawing fluid under pressure to and from the chamber during each complete cycle of the engine.

10. In a device for admitting fuel into an internal combustion engine having a cylinder, a conduit establishing communication between the interior and the exterior of the cylinder, and a piston reciprocable in the cylinder, the improvement comprising a fuel valve adapted to control the admission of fuel into the cylinder, means for normally maintaining the valve in closed position, a housing associated with the valve, a fixed partition dividing the interior of the housing into a fluid compartment and a valve actuating compartment, a movable partition forming a wall of the actuating compartment and responding to fluid pressure for actuating the valve against the action of said means, a port for establishing communication between the fluid compartment and the actuating compartment, and means including a plurality of valve controlled passages adapted to communicate with the conduit for introducing and withdrawing fluid under pressure into and from the compartments during each complete cycle of the engine.
